UNITED STATES PATENT OFFICE.

HERMAN GILES, OF MINNEAPOLIS, MINNESOTA.

ARTIFICIAL FINGER.

Application filed June 22, 1923. Serial No. 647,032.

To all whom it may concern:

Be it known that I, HERMAN GILES, a citizen of the United States, residing at Minneapolis, in the county of Hennepin 5 and State of Minnesota, have invented certain new and useful Improvements in Artificial Fingers; and I do hereby declare the following to be a full, clear, and exact description of the invention, such as will enable others skilled in the art to which it 10 pertains to make and use the same.

My invention has for its object to provide an artificial finger having means for attaching the same to a hand.

15 To the above end, the invention consists of the novel devices and combinations of devices hereinafter described and defined in the claims.

In the accompanying drawings, which 20 illustrate the invention, like characters indicate like parts throughout the several views.

Referring to the drawings:

Fig. 1 is a perspective view of a mutilated 25 hand having all of the fingers removed therefrom with the exception of the thumb;

Fig. 2 is a perspective view showing the invention applied to said hand;

Fig. 3 is a perspective view of the invention 30 removed from the hand;

Fig. 4 is a detail view with some parts sectioned on the line 4—4 of Fig. 3;

Fig. 5 is a view of the finger-like member 35 removed from its holder; and

Fig. 6 is a view of the hook member adapted to be attached to the holder in place of the finger-like member.

The numeral 7 indicates a mutilated hand 40 on which all of the fingers have been removed with the exception of the thumb.

The invention includes a rigid yoke-like holder 8 adapted to straddle the hand 7 between the thumb and the joint of the index finger and bear thereagainst. Secured to

45 the prongs of the yoke-like holder 8 is a wrist-like band 9 having a pair of buckle-equipped straps 10 by which said band can be adjustably secured around the wrist of the hand 7 to securely hold the holder in position.

A finger-like member 11 is detachably secured to the transverse portion of the yoke-like holder 8 by providing said member with a screw-threaded stem 12 adapted to

50 be screwed into an outstanding boss on the transverse portion of said holder 8. The

yoke-like holder 8 and wrist band 9 firmly secure the finger-like member 11 to the hand so that articles may be picked up between the thumb and the finger-like member 11 by pressing the same with the thumb against said member. 60

Interchangeably usable with the finger-like member 11 is a hook-like member 13 having a screw-threaded stem 14, of the same size as the stem 12, for detachably securing the same to the holder 8. 65

What I claim is:

1. A yoke-like holder adapted to engage a hand between the thumb and the joint of 70 the index finger thereof and having means for attaching the same to the hand, and a finger-like member on the transverse portion of said holder for co-operation with the thumb of the hand. 75

2. The structure defined in claim 1 in which the finger-like member is detachable.

3. A yoke-like holder adapted to engage a hand between the thumb and the joint of 80 the index finger thereof and having means for attaching the same to the hand, and interchangeably usable finger-like members applicable to the intermediate portion of the holder.

4. A rigid yoke-like member adapted to 85 straddle a hand between the thumb and joint of the index finger and having means for attaching the same to the hand, and a finger-like member attached to said holder for co-operation with the thumb of the hand. 90

5. A rigid yoke-like member adapted to straddle a hand between the thumb and joint of the index finger and having means for attaching the same to the hand, and a finger-like member having detachable 95 screw-threaded engagement with the holder for co-operating with the thumb of the hand.

6. A rigid yoke-like holder adapted to straddle a hand between the thumb and 100 joint of the index finger, a wrist band attached to the prongs of said holder, and a finger-like member attached to said yoke-like holder for co-operation with the thumb of the hand. 105

7. The structure defined in claim 6 in which the wrist band is provided with a buckle-equipped strap.

In testimony whereof I affix my signature.

HERMAN GILES.
